FIG. 5

FIG. 6

FIGURE 1 is a front perspective view of a typewriter carriage showing our new design, the broken lines showing the parts of a typewriter being for illustrative purposes only;

FIGURE 2 is a top plan view of the typewriter carriage shown in FIGURE 1;

FIGURE 3 is a front elevational view thereof;

FIGURE 4 is a rear elevational view thereof;

FIGURE 5 is an end elevational view as seen from the left of FIGURE 3; and

FIGURE 6 is an end elevational view as seen from the right of FIGURE 3.

We claim:

The ornamental design for a typewriter carriage, substantially as shown and described.
